(57) **CLAIM**

The ornamental design for a blood pressure measuring apparatus for veterinary use, as shown and described.

DESCRIPTION

FIG. 1 is a top view of a blood pressure measuring apparatus for veterinary use showing my new design;

FIG. 2 is a rear view thereof;

FIG. 3 is a front view thereof;

FIG. 4 is a left view thereof;

FIG. 5 is a right view thereof;

FIG. 6 is a bottom view thereof;

FIG. 7 is a rear perspective view thereof; and,

FIG. 8 is a side perspective view thereof.

The broken lines in the drawings illustrate portions of the blood pressure measuring apparatus for veterinary use that form no part of the claimed design.
